UNITED STATES PATENT OFFICE.

FREDERICK W. COY, OF BOSTON, MASSACHUSETTS, ASSIGNOR TO GEORGE H. P. FLAGG, OF SAME PLACE.

BUFFING-MACHINE FOR BOOTS AND SHOES.

SPECIFICATION forming part of Letters Patent No. 247,315, dated September 20, 1881.

Application filed March 30, 1881. (No model.)

To all whom it may concern:

Be it known that I, FREDERICK W. COY, of Boston, in the county of Suffolk and State of Massachusetts, have invented certain Improvements in Machines for Buffing the Bottoms and Shanks of Soles, of which the following is a full, clear, concise, and exact description, reference being had to the accompanying drawings, in which—

10 Figure 1 is a front elevation, and Fig. 2 a side elevation, of a machine embodying my invention. Fig. 3 is a section on line xx of Fig. 4, and both these figures are details illustrating one feature of my invention. Figs. 5, 15 6, and 7 are views of the shank-wheel, Fig. 5 being an elevation, Fig. 6 a plan, and Fig. 7 a vertical section, of part of the wheel.

20 My machine consists of a suitable frame or pedestal, A, carrying the driving-shaft B and the fan C, all too well known to need description.

25 The shaft D carries the buffing-rolls a a , for buffing the bottoms, and the shank-wheel b , for buffing the shanks. The buffing-rolls a may be called “pulleys,” as they, in connection with the idler-pulleys d , carry an abrasive belt, f , by which the buffing is performed. This belt is shown in place on the left of Fig. 1. The shank-wheel b is of novel construction, fully 30 described below, and carries a strip of sandpaper or other abrasive material for buffing the shanks.

35 One feature of my invention relates to the combination of the two pulleys a and d ; and it consists in mounting one of them (in this instance the idler d) in such a manner that it can be moved not only toward pulley or roll a , in order that the belt f may be readily put in place and removed, and away from pulley 40 a , in order to tighten belt f , but also so that its axis may be readily adjusted in position with relation to the axis of the roll or pulley a , this last being the distinguishing characteristic of this part of my invention, as fully explained below.

45 The best form of mechanism known to me for embodying my invention is that shown in the drawings, in which d' is an arm journaled

50 at d^2 to the frame of the machine. On this arm d' is journaled at d^4 the yoke d^3 , and in this yoke d^3 the idler d is journaled. It will be seen that motion of the arm d' on its axis d^2 will carry idler d toward or away from roll a , and that motion of yoke d^3 on its axis d^4 will alter the relation of the axis of idler d and roll a .

55 To put on or take off the belt f , the arm d' is lowered, thus bringing the idler d so near to roll a that the belt can be readily put on or taken off. By raising arm d' the idler d is carried away from roll a far enough to tighten belt f . If the belt f were true and the idler d and roll a also true, and their axes parallel, the belt would of course run true, even at the high speed at which these machines are run— 60 commonly over two thousand revolutions a minute—but as the roll a must be covered with felt or some other soft elastic material to adapt it for buffing soles, it is very difficult to keep the belt f in place; and the main object 65 of my invention is to remedy this difficulty. I have done this by so mounting idler d that the direction of its axis can be readily shifted within the necessary limits by the operator, and while the machine is running.

70 The projecting arm d^5 of yoke d^3 has a nut, d^6 , mounted in its forked end. A screw, d^7 , passes through this nut d^6 , and this screw is connected with the front end of the arm d' . When the machine is started up the belt f 75 will usually tend to work sidewise, and this is at once corrected by the operator by means of screw d^7 , by turning that screw in one or the other direction, according as the belt moves sidewise toward or away from the frame of the 80 machine.

85 Another feature of my invention consists in using a spring-pressure to tighten belt f —that is to say, instead of taking hold of arm d' directly to raise it in order to tighten the belt f , the lever d^8 is used, and this lever is connected to arm d' by means of spring d^9 . This lever d^8 is held up by the spring-catch d^{10} , and when so held up the tension of spring d^9 strains the belt, that tension being adjusted to give the desired strain.

The shank-wheel b is so constructed that its rim b can be sprung to clamp the ends of the abrasive strip.

In that form of my invention shown in Figs. 5, 6, and 7 of the drawings the strip is applied by first inserting one end of it in the inclined slit b^2 , then carrying it in the direction of the arrow, Fig. 5, around the wheel, inserting its other end in the slit b' , and clamping it by springing the rim of wheel b , so as to cause the walls of slit b' to press hard upon the ends of the abrasive strip. The clamping is done by turning shaft b^3 by means of the finger-piece b^4 , (fast to shaft b^3 ,) the cams b^5 b^6 (fast to the shaft b^3) acting on projections b^6 b^6 (fast to the rim of wheel b , one on either side of slit b') to force the walls of slit b' toward each other. The shaft b^3 is supported by the inner part of spoke b^7 , the rest of that spoke being omitted in casting the wheel (or cut off after the wheel is cast) to make room for the mechanism b^3 b^4 b^5 , by which the clamping-jaws are operated.

The shank-wheel is, of course, covered with felt to serve as a cushion for the abrasive strip, the felt being applied in the usual way, except that it must also have a slit in it corresponding with slit b' , so that it will not prevent the insertion of the ends of the abrasive strip, as above described.

The dust from the buffing-rolls a and shank-wheel b is carried away by the fan in the usual manner.

The belt f is made in any suitable way, the belt used in practice being that described in the application of G. H. P. Flagg and William Gordon, filed December 29, 1880.

To renew a worn-out belt and replace it by a fresh one, the operator releases spring-catch d^{10} , and thereby allows lever d^8 and arm d^9 to fall. He then removes the worn belt, puts on a fresh one, and raises the front end of lever d^8 until it catches upon spring-catch d^{10} , at the same time causing the new belt to run true by manipulating screw d^7 . This is the work of a few minutes.

The buffing is done just as if the rolls a a

were the usual buffing-rolls, for although my machine is the first, so far as I know, in which a buffing-roll was used as a pulley—that is, with a belt and an idler—the operation of buffing is not changed thereby, any operator skilled in the use of buffing-machines having the ordinary buffing-roll finding no difficulty in the use of my machine so far as concerns the buffing.

The renewal of the abrasive material is, of course, wholly different in my machine from what it is in any other buffing-machine known to me; but this is readily learned by the operator.

I am aware that abrasive belts are old, and that I am not the first to use an abrasive belt for buffing shoe-soles. (See English patent to Robert Flude, No. 2,861 of 1865.)

I am also aware of the patent to P. F. Randolph, No. 95,265, dated September 28, 1869, Reissue No. 4,127, September 30, 1870, in which the article to be abraded was held against that part of the belt which was in contact with the rubber-covered pulley or roll, and I disclaim all that is described in those patents.

What I claim as my invention is—

1. In combination, roll a , pulley d , and mechanism, substantially such as is described, for moving pulley d toward and from roll a , and for adjusting the axis of the pulley with relation to the axis of the roll, as and for the purpose specified.

2. In a machine for buffing boots and shoes, the spring d^9 , arranged as described with reference to roll a and pulley d , whereby the strain on belt f depends upon the tension of spring d^9 , as set forth.

3. A shank-wheel provided with the straight slit b' and the inclined slit b^2 , as shown, and adapted to hold the abrasive strip, substantially in the manner and for the purpose set forth.

FREDERICK W. COY.
